UNITED STATES PATENT OFFICE.

EMIL GEORGE HESS AND WILLIAM HESS, OF WEST TORONTO JUNCTION,
CANADA, ASSIGNORS TO ALICE GRACE HESS, OF SAME PLACE.

DESIGN FOR A KNOB OR PULL.

SPECIFICATION forming part of Design No. 21,198, dated December 1, 1891.

Application filed April 23, 1891. Serial No. 390,171. Term of patent 14 years.

To all whom it may concern:

Be it known that we, EMIL GEORGE HESS and WILLIAM HESS, both of the town of West Toronto Junction, in the county of York, in the Province of Ontario, Canada, have invented and produced a new and original Design for Knobs or Pulls, of which the following is a specification, reference being had to the accompanying drawing, forming a part thereof.

5 The figure is a perspective view of our design.

10 The general form of our design is that of a knob or pull having an approximately flat

surface with a series of parallel grooves extending in both directions across the face of the knob to the periphery, leaving squares and portions of squares with their edges rounded off down to the bottom of the lines.

15 What we claim is—

The design for a knob or pull, as herein shown and described.
